US00D668198S

(12) **United States Design Patent**
Platto et al.

(10) **Patent No.:** US D668,198 S
(45) **Date of Patent:** ** Oct. 2, 2012

(54) **VEHICLE WHEEL**

(75) Inventors: **Gordon M. Platto**, Troy, MI (US);
Bradley Alan Richards, Bloomfield
Hills, MI (US); **Shawn Sung Yu**,
Shanghai (CN); **Timothy Doyle**, Royal
Oak, MI (US); **Amy Kim**, New York,
NY (US)

(73) Assignee: **Ford Motor Company**, Dearborn, MI
(US)

(**) Term: **14 Years**

(21) Appl. No.: **29/411,532**

(22) Filed: **Jan. 23, 2012**

(51) **LOC (9) Cl.** 12-16

(52) **U.S. Cl.** **D12/211**

(58) **Field of Classification Search** D12/204-213;
301/37.101, 64.101, 65, 64.201

See application file for complete search history.
